(57) CLAIM

The ornamental design for a combined tray and brush holder for a surface cleaning apparatus, as shown and described.

DESCRIPTION

FIG. 1 is a front, right perspective view of a combined tray and brush holder for a surface cleaning apparatus showing my new design;

FIG. 2 is a top view thereof;

FIG. 3 is a rear view thereof;

FIG. 4 is a front view thereof;

FIG. 5 is a right side view thereof;

FIG. 6 is a left side view thereof; and,

FIG. 7 is a front, right perspective view thereof, the upright surface cleaning apparatus and two brushes shown in broken lines form no part of the claimed design.
